DESIGN FOR A SOUND-ON-FILM RECORDER CASING

Walter Herman Bach, Los Angeles, Calif., assignor to E. M. Berndt Corporation, Los Angeles, Calif.

Application August 5, 1940, Serial No. 94,255

Term of patent 14 years

To all whom it may concern:

Be it known that I, Walter H. Bach, a citizen of the United States, residing at Los Angeles, in the county of Los Angeles and the State of California, have invented a new, original, and ornamental Design for a Sound-on-Film Recorder Casing, of which the following is a specification, reference being had to the accompanying drawing forming a part thereof.

In the drawing:

Fig. 1 is a perspective view of a sound-on-film recorder casing showing the front and one side of the casing and illustrating my new design.

Fig. 2 is a perspective view of the sound-on-film recorder casing shown in Fig. 1, but illustrating the back and the opposite side of the casing from that shown in Fig. 1.

I claim:

The ornamental design for a sound-on-film recorder casing, as shown.

WALTER HERMAN BACH.
